DESIGN FOR A NURSING BOTTLE SUPPORT

Vernon F. Hoobler, Cleveland, Ohio

Application May 8, 1933. Serial No. 48,041

Term of patent 7 years

To all whom it may concern:

Be it known that I, VERNON F. HOOBLER, a citizen of the United States, residing in Cleveland in the county of Cuyahoga and State of Ohio, have invented a new, original, and ornamental Design for a Nursing Bottle Support of which the following is a specification, reference being had to the accompanying drawing, forming part thereof.

Figure 1 is a perspective view of a nursing bottle support, showing my new design; and

Figure 2 is a side elevation of the device shown in Figure 1.

I claim:

The ornamental design for a nursing bottle support substantially as shown.

Signed by me this 5th day of May, 1933.

VERNON F. HOOBLER.
